Des. 226,940
Patented May 15, 1973

226,940

DEEP FRIER

Michael Lax, New York, N.Y., assignor to
Copco, Inc., New York, N.Y.

Filed July 2, 1971, Ser. No. 159,582

Term of patent 14 years

Int. Cl. D7—02

U.S. Cl. D44—1 F

FIG. 1 is a perspective view of a deep frier showing my new design, in closed condition;

FIG. 2 is a perspective view from the left side of FIG. 1;

FIG. 3 is a perspective view with the cover removed and with the basket in raised position;

FIG. 4 is a perspective view of the cover member; and

FIG. 5 is a reduced scale bottom plan view.

I claim:

The ornamental design for a deep frier, substantially as shown and described.
